NOSE GUARD

James W. Welsh, Providence, R. I., assignor to
The Welsh Manufacturing Company, Providence, R. I., a corporation of Rhode Island

Original application December 29, 1933, Serial No. 704,393. Divided and this application April 28, 1934, Serial No. 722,895. Renewed January 30, 1937

3 Claims.

(Cl. 88—49) The present invention relates to nose guards for ophthalmic mountings, particularly nose guards comprising non-metal material. The present application is filed as a division of application Serial No. 704,393, filed December 29, 1933, and is in response to a requirement by the Patent Office for division.

In Letters Patent of the United States, No. 1,955,843, granted April 24, 1934, there is disclosed a new and improved nose guard comprising an unbacked, non-metal, nose rest that has essentially the flexibility, softness and other characteristics of the non-metal material, but that is nevertheless reinforced by a metal support to compensate for the weakness of such non-metal material.

An object of the present invention is to provide a new and improved guard of the character disclosed in the said Letters Patent.

According to the construction disclosed in the said Letters Patent, the metal support extends entirely, or substantially, through the non-metal nose rest, from the rear face to, or near to, the front face. This introduces the actuality, or, at least, the possibility, of the metal coming into contact with the skin of the wearer's nose, and another object of the invention is to provide a novel guard of the above-described character that shall eliminate this defect.

In the guard of the said Letters Patent, furthermore, the metal and the non-metal parts are secured together in such way that they sometimes have a tendency to become separated from each other, and still a further object of the invention, therefore, is to provide a new and improved guard of the above-described character the metal and the non-metal parts of which shall be joined together so securely as to be almost inseparable.

Another object is to provide a new and improved nose-guard support.

A further object is to provide a novel connection between the guard and its support.

Other and further objects will be explained hereinafter and will be particularly pointed out in the appended claims.

The invention will now be explained in connection with the accompanying drawings, in which Fig. 1 is a rear elevation of an ophthalmic mounting embodying a nose-guard according to the present invention; Fig. 2 is a plan of the same; Figs. 3 and 4 are enlarged sections taken upon the lines 3—3 and 4—4 of Fig. 1, looking in the directions of the arrows; Fig. 5 is a rear elevation of the novel guards of the present invention; Fig. 6 is a section taken upon the line 6—6 of Fig. 5,

looking in the direction of the arrows; Fig. 7 is a perspective of the novel, nose-rest support of the present invention, prior to its assembly with the nose rest; Fig. 8 is a section taken upon the line 8—8 of Fig. 7, looking in the direction of the arrows; Fig. 9 is a section taken upon the line 9—9 of Fig. 8, looking in the direction of the arrows; Fig. 10 is a section taken upon the line 10—10 of Fig. 5, looking in the direction of the arrows; Fig. 11 is a plan illustrating a step in the manufacture; Fig. 12 is a section taken upon the line 12—12 of Fig. 11, showing the relative positions of the parts prior to the descent of the movable die; and Fig. 13 is a similar section, showing the parts in the relative positions occupied after the descent of the movable die.

Each nose rest 10 is composed of some non-metal material, like celluloid, unbacked by any reinforcing or supporting member, such as metal. Each nose rest 10 is provided with an opening 14 extending, in the direction of the thickness dimension of the nose rest, from the inner face 18 of the nose rest, inward a substantial distance toward the outer face 16, as illustrated more particularly in Figs. 6, 10 and 13. The thickness distance between the oppositely disposed faces 16 and 18 is, of course, small compared with the dimensions along said faces in the direction of the length or the width of the nose rest. A metal arm 8 has integral therewith a metal member 20, preferably in the form of a circular disk, that is inserted in the opening 14. The metal member 20 may, however, have other shapes, such as the long and narrow shape illustrated and described in a copending application, Serial No. 758,392, filed December 20, 1934. The opening 14, into which the metal disk or other member 20 is received, extends over a distance, in a direction along the faces 16 and 18, that is of substantial extent compared with the dimensions of the guard, so as to provide for the use of a substantial amount of metal, which is of corresponding extent. The thickness of the metal disk or other member 20 is small compared with its diameter or length, as is shown more particularly in Figs. 4, 6 to 10, 12 and 13, though this metal thickness is very thin compared with the thickness of the nose rest, as is illustrated more particularly in Figs. 4, 6, 10 and 13. The parts are rigidly secured together, as hereinafter described, thus forming an integral, one-piece, unbacked non-metal guard, except for the metal portion 20.

The metal disk 20 may originally be more or less concavo-convex, or cup shaped, as illustrated

more particularly in Figs. 7, 8, 9 and 12, in which event it will become substantially flattened out, as illustrated in Figs. 6, 10 and 13, during the assembly process of the nose rest 10 with the 5 metal support 8, as hereinafter described. A stem 29 is originally cut out of the metal sheet of which the arm 8 is constituted by slotting at 31, from the periphery 33 of the disk inward to about the center of the disk, and bending the stem 29 10 out of the plane of the sheet at the convex side, as illustrated in Figs. 7, 8 and 9. Concavo-convex prongs 35 and 37 are thus formed at the sides of the slot 31. It is the thus slotted, pronged disk 20 that is later embedded in the opening 14 of 15 the unbacked nose rest. The stem 29 may, however be formed in other ways, without slotting, as illustrated and described in said application.

To effect this embedding, the metal member 20 is first placed on a fixed die 41. As illustrated 20 in Fig. 12, the stem 29 is shown inserted in a correspondingly shaped-and-sized opening 39 of the fixed die 41, with the disk 20 exposed and its concave side facing away from the die 41. A strip 43 of the non-metal material is fed through 25 a guide 45 and over the metal member 20. During its passage through the guide 45, the strip 43 may be very slightly heated in any desired way, preferably electrically, electric terminals for the heater being shown at 47. During a moment of 30 pause in the feed of the strip 43, a movable die 49 is caused to descend upon the strip, from the position illustrated in Fig. 12 to the position illustrated in Fig. 13.

Owing to the above-described relative dimensions of the parts, and the concavo-convex shape 35 of the metal disk 20, as well as the method of manufacture of the disk 20, its periphery 33 is relatively sharp, which sharpness is materially contributed to by the prongs 35 and 37. As the 40 concave side of the disk 20 is disposed adjacent to the under face of the strip 43, as shown in Fig. 12, the sharp portions of the disk 20 are caused to cut their way into this heated, under face of the strip 43 during the application of 45 pressure by the descending die 49. The same action takes place even when the metal member is unslotted. During this digging action, the metal member 20 displaces the non-metal material in this heated under-face area of the metal 50 disk, thus cutting its own opening 14 into the non-metal material, of a size and shape exactly corresponding to the size and shape of the metal member 20. The metal disk 20 thus becomes securely embedded in the opening 14, in the position 55 formerly occupied by the displaced, non-metal material.

The movable die 49 is provided with a cutting face 51 that, in cooperation with a corresponding face 53 of the fixed die 41, severs from the strip 60 43, simultaneously with the before-described pressing operation, a portion of the non-metal material that has the shape and size desired for the unbacked, non-metal nose rest 10, as illustrated in Figs. 1 to 6, 10 and 13. The active faces 65 55 and 57 of the dies 49 and 41, furthermore, are curved, as illustrated in Figs. 12 and 13, to impart the desired, curved shape to the non-metal nose rest 10.

The face 57 of the fixed die 41 has a circular 70 depression 59 into which the non-metal material of the strip 43 is caused to flow or roll over against the under or convex face of the metal member 20, thus locking the metal member 20 securely into the opening 14, as is illustrated more 75

particularly at 61 in Figs. 3 to 6, 10 and 13. The metal becomes thus embedded in under the flowed-over portion 61 of the non-metal material. The pressing force exerted by the moving die 49 is sufficient, not only to press the heated 5 zylonite or other non-metal material into the depression 59, but also to flatten out the concavo-convex disk during the curving of the non-metal nose rest 10, as before described. This flattening 10 out of the metal further acts to embed the metal 15 in under the flowed-over portion 61 of the non-metal material. When the non-metal material becomes chilled, it is almost impossible, without 20 breaking the metal stem 29, to pull the metal member 20 out of its embedded position. As the 25 relatively large metal member 20 is forced into the celluloid sidewise, instead of along its edge periphery, a greater holding action is obtained. It requires great pressure to force the disk 20 into the zylonite, and great pressure to remove it. This would be true even if the metal member 20 had been unslotted at 31, but this slot 31, and the prongs 35, 37 adjacent thereto, contribute to the holding action of the metal in the zylonite.

The described method has been found to eliminate 25 all possibility of the parts becoming separated. The stem 29 is later looped into the openings 6 about the tongue 12, as before described.

Modifications will occur to persons skilled in 30 the art, and all such are considered to fall within the spirit and scope of the invention as defined in the appended claims.

What is claimed is:

1. A guard having, in combination, an unbacked 35 non-metal nose rest provided with an opening extending, in the direction of the thickness dimension of the nose rest, from one face of the nose rest inward a substantial distance toward the opposite face of the nose rest, and a metal support for the nose rest comprising a disk having a 40 stem cut therefrom from the periphery of the disk inward, the stem being bent out of the disk to provide a slot in the disk, whereby prongs are 45 formed in the disk at the sides of the slot, the slotted, pronged disk being embedded in the said opening of the unbacked nose rest.

2. A guard having, in combination, an unbacked 50 non-metal nose rest provided with an opening extending, in the direction of the thickness dimension of the nose rest, from one face of the nose rest inward a substantial distance toward the opposite face of the nose rest, the thickness distance of the nose rest between the said faces being small compared with the dimensions along 55 said faces in the direction of the length or the width of the nose rest, and a metal support for the nose rest comprising a disk having a stem cut therefrom from the periphery of the disk inward, the diameter of the disk being substantial 60 compared with the dimensions of the nose rest, the thickness of the disk being small compared with the said diameter and being very thin compared with the said thickness distance, the said 65 stem being bent out of the disk to provide a slot in the disk, whereby prongs are formed in the disk at the sides of the slot, the slotted, pronged disk being embedded in the said opening of the unbacked nose rest.

3. A guard comprising a non-metal nose rest 70 having two oppositely disposed faces the distance between which, in the direction of the thickness dimension of the nose rest, is small compared with the dimension along said faces in the direction of the length or the width of the nose rest, the nose rest having an opening extending from one of 75

said faces toward the other face over a distance, in a direction along said faces, that is of substantial extent compared with the dimensions of the nose rest, and a metal support for the nose 5 rest having embedded in the said opening a disk of corresponding extent, whereby the metal support serves as a reinforcement to compensate for

the weakness of the non-metal material, the disk having a stem cut therefrom from the periphery of the disk inward, the stem being bent out of the disk to provide a slot in the disk, whereby prongs are formed in the disk at the sides of the slot. 5
